UNITED STATES PATENT OFFICE.

HENRY BLACKMAN, OF BELMAR, NEW JERSEY.

VENTILATING TUNNELS.

No. 852,995.

Specification of Letters Patent.

Patented May 7, 1907.

Application filed April 16, 1906. Serial No. 311,938.

To all whom it may concern:

Be it known that I, HENRY BLACKMAN, a citizen of the United States, residing at Belmar, in the county of Monmouth and State of New Jersey, have invented certain new and useful Improvements in Ventilating Tunnels, of which the following is a specification.

The invention aims to provide a system or means of purifying the atmosphere in railway tunnels in which there are a number of entrances arranged along the length of the tunnel, and outside means are arranged for withdrawing bad air from the tunnel at points intermediate between such entrances, the ventilation being assisted if desired by simultaneously forcing air in at the entrances; the particular features of novelty being referred to in detail herein and stated briefly in the claims.

I do not claim broadly in this application ventilating by inducing short air currents from the entrances to the intermediate points, this being claimed in my application No 348,744 filed December 20, 1906; and the present application being limited to positive air-withdrawing means outside of the tunnel for sucking the air out at such intermediate points.

The accompanying drawings illustrate the application of the system to a tunnel similar to the New York subways.

Figure 1 is a transverse section through the tunnel; Fig. 2 is a plan of a portion thereof; Figs. 3 and 4 are vertical cross-sections of the tunnel illustrating outlets or inlets thereof. Figs. 5 and 6 are respectively a diagrammatic plan and a section through an entrance where air is being forced in.

Referring to the particular embodiment of the invention illustrated, A is the tunnel through which the cars B travel. The usual stations C are provided at suitable intervals. Between each two stations is located a suction pump or fan D communicating with the interior of the tunnel near the roof and carrying away the air therefrom to any suitable point, such as the chimney E of a power house. The operation of the suction pump D effects a very rapid removal of the most vitiated air near the top of the tunnel. The deficiency is made up by an additional supply of air coming down through the stations C.

The openings through which air is withdrawn from the tunnel or introduced there-

into must be specially arranged to prevent the admission of water. A number of suitable arrangements are shown in Figs. 3 and 4, any one of which may be used, or any number of them in combination. The air may be passed for example through a lamp-post Y, open at the top, and provided with a hood Z to keep out rain, a fan a being arranged at the bottom or at the top of the lamp-post. By arranging it at the top of the lamp-post, an economy of space will be effected, since there would be no interference with traffic, or a column b for supporting a letter box or other device may carry away the bad air.

Where an opening at the level of the street is desired, there may be provided a man-hole c (Fig. 3) with a hood d which sheds the rain into a gutter e connecting by a pipe f with the sewer g. An electric fan h may be operated by current from wires running to the underground conduit j. A separate compartment k large enough for a man to enter, is provided at the side so as to have access for starting or stopping the fan and for making any necessary repairs. Or a similar outlet or inlet l may be provided along the edge of the sidewalk, as shown in Fig. 4. Assuming that this is to be used as an inlet for fresh air, a screen m is provided through which air must pass in order to enter the conduit n leading to the tunnel. Rain water will collect in a depression in the floor, and will be carried off to the sewer g. The coarsest dirt will be restrained by the grating on the top of the man-hole, and the finer dirt by a grating o, near the bottom. A valve p will be used to cut off the entrance to the conduit n in case of heavy rain or choking of sewers, this valve being in a second compartment accessible by means of a removable cover plate q.

Various arrangements may be used for forcing in air at the entrances as above referred to. For example as shown in Fig. 5, one or more fans r may be mounted upon brackets s near the ends of the stations with their outlets directed toward the space between stations, and with their inlet pipes t passing up through the sidewalk or roadway overhead, with suitable means for intercepting dirt.

Though I have described with great particularity of detail certain specific processes embodying the invention, yet it is not to be understood that the invention is limited to the exact process described.

Various modifications may be made by

those skilled in the art, without departure from the invention.

What I claim is:—

1. Means for purifying the atmosphere in a railway tunnel having a number of entrances along its length, comprising means lying entirely outside of the space within the tunnel for withdrawing bad air from the tunnel at points approximately half way between such entrances so as to draw from two adjacent entrances and create two ventilating currents in opposite directions from the two entrances toward the half way point. 35
2. Means for purifying the atmosphere in a railway tunnel having a number of entrances along its length, comprising means lying entirely outside of the space within the tunnel for withdrawing bad air from the tunnel at points approximately half way between such entrances so as to draw from two adjacent entrances and create two ventilating currents in opposite directions from the two entrances toward the half way point, the tunnel being closed except at the entrances and at said intermediate points, so that the withdrawal of bad air at said intermediate points induces an inflow of fresh air at the entrances only. 40
3. Means for purifying the atmosphere in a railway tunnel carrying a plurality of tracks for trains moving in opposite directions and constructed without partitions and having a 45
4. Means for purifying the atmosphere in a railway tunnel having a number of entrances along its length, comprising means lying entirely outside of the space within the tunnel for withdrawing bad air from the tunnel at points approximately half way between such entrances so as to draw from two adjacent entrances and create two ventilating currents in opposite directions from the two entrances toward the half way point, in combination with means for forcing air in at the entrances. 50

In witness whereof, I have hereunto signed my name in the presence of two subscribing witnesses.

HENRY BLACKMAN.
